* cited by examiner

Primary Examiner — Keith J Wilson*Assistant Examiner* — Carolyn W Davis(74) *Attorney, Agent, or Firm* — Hemisphere Law, PLLC;
Zhigang Ma(57) **CLAIM**

The ornamental design for a socket fan as shown and described.

DESCRIPTION

FIG. 1 is a front, right, and bottom perspective view of a socket fan, showing my new design;

FIG. 2 is a rear, right, and top perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the socket fan that form no part of the claimed design.
